UNITED STATES PATENT OFFICE.

HARRY BELOIT, OF SAN PEDRO, CALIFORNIA, ASSIGNOR TO ECONOMY PUMP AND OIL TOOL COMPANY, OF LOS ANGELES, CALIFORNIA, A CORPORATION OF CALIFORNIA.

DEEP-WELL PUMP.

Application filed December 14, 1925. Serial No. 75,379.

This invention relates to and has for a main object the provision of an improved type of deep well pump, particularly adapted for use in oil wells, and it is also an object to 5 provide a pump for the purpose stated which will afford a greater piston displacement than in other obtaining types of pumps, and also a greater volume of oil admitted to the pump barrel below the piston.

10 A further object is to provide in a deep well pump means for lubricating the piston in its travel over the pump cylinder and to so arrange the elements of the pump that the entrance of sand into the pump during the continued operation thereof will not affect the operation or impair any of the working parts.

A still further object is to provide a barrel, closed at both ends and insertible into a well casing, a stationary cylinder stationarily held 20 in and attached to one head of the barrel and of smaller diameter than the barrel, and a piston encompassing the cylinder and enclosed by the barrel, and arranged for connection with sucker rod by means of which 25 the piston is reciprocated in the barrel.

Another object is to provide a composite piston, of separable sections, including rings ground to fit the outer periphery of the cylinder, and of sufficiently greater diameter 30 than the cylinder so as to provide an annular space around the cylinder for containing a quantity of lubricant whereby the piston may be constantly lubricated during the operation of the pump, and for otherwise rendering the 35 operation of the pump more effective than is possible in other types of pumps.

Other objects include providing suitable valves in the barrel and in the piston head for regulating and controlling the admission 40 of liquid to the pump cylinder and its discharge therefrom.

In connection with this application reference is had to a Patent, Number 1,396,243 granted to me on the 8th day of November, 45 1921, for deep well pumps.

In the accompanying drawing I have shown a preferred embodiment of my invention, subject to modification within the scope of the appended claims, without departing 50 from the spirit of my invention.

In said drawings:

Fig. 1 is a sectional elevation of my improved pump, as a unit, and apart from a well in which it is adapted to be used.

55 Figs. 2, 3, 4 and 5 are, respectively, hori-

zontal cross sections of the same on lines, 2-2, 3-3, 4-4, and 5-5 of Fig. 1.

I have shown my improved pump in the form of a unit removed from the usual well casing (not shown) and assembled in readiness for insertion bodily into the well.

In the pump proper, as shown, B represents a substantially elongated barrel of smaller diameter than the smallest section of the well casing, and it is provided at its upper end with a head H having a flange 1 abutting the end of the barrel, an externally threaded extension 2 over which the upper end of the barrel is threaded, and a tapered and threaded extension 3 to which a section of pump 70 casing (not shown) is adapted to be threaded. Said head H has a central internally threaded recess 4 into which the upper end of an elongated cylinder C is threaded and held in stationary position within the barrel B, the same being depended into the barrel, as shown in Fig. 1.

The bottom of barrel B has a head H¹, similar to head H, threaded into and for closing the lower end of the barrel. Said head H¹ is 80 internally threaded at 5 for receiving the upper end of a gas anchor (not shown) and the central passage 6 admits the liquid from the well into the barrel B. Head H¹ is also externally threaded at 7 for attachment to a 85 pipe (not shown) depending further into the well, as in other types of pumps.

Barrel B is provided at the head H¹ with a foot valve V held in a cage A of usual form and said cage is provided with a base 8 90 which is flanged at 9 and rests upon the inner end of the head H¹. Cage A has a threaded extension 10 screwed into the head H¹ and having a central passage 11. The upper end of said passage forms a seat 12 for valve V, 95 and said passage is normally closed by the ball valve V. Said cage is upwardly extended, however, so as to permit of ample movement of the valve V to effect the complete opening of the valve port 11.

The piston P is of composite, or sectional form, and is slidably disposed in the barrel and between the inner periphery of the same and the outer periphery of the cylinder C, but the piston substantially clears the wall 105 of the barrel. Said piston has a head h at its lower end, a ring r at its upper end and an intermediate ring r' therebetween, said rings being connected by means of tubular sections t, and t'. Section t is threaded at one end on 110

an extension 13 of ring r , and at its other end on a similar extension 14 on ring r' . Likewise section t' is threaded at one end on an extension 15 of ring r' and at its other end on an extension 16 of head h .

Rings r and r' are bored and ground to fit nicely the periphery of cylinder C and the uppermost section t of the piston is substantially larger in diameter than the cylinder C so as to provide an annular space 17 around the cylinder and between the rings r and r' for the reception of a quantity of grease, which will serve to thoroughly lubricate the piston during the continued operation of the pump, and at the same time prevent the entrance of sand and grit between the cylinder and piston rings. This structure also serves to prevent leakage of the liquid around the cylinder. The space 17 may be filled with grease prior to the positioning of the pump in the well by removing a filling plug 18 which is threaded into the wall of the section t .

Piston P is provided with an inlet valve V^1 , similar to the foot valve V, the cage D of said valve being secured to the piston head h , and the pump sucker rod R being secured to the head 19 of the cage D, as shown.

In operation, the piston P, including rings r and r' , pipe sections t and t' , head h and valve V^1 with its cage D are assembled as a unit, and grease is packed in the uppermost section between rings r and r' . The barrel B is then partially assembled with the bottom head H^1 and valve V and cage A secured thereto as described; cylinder C is secured to head H and piston P positioned on the cylinder C; whereupon the cylinder and piston are positioned in the barrel and the head H secured to the upper end of barrel B. The entire unit may then be bodily lowered into the well to the proper depth with the barrel almost if not entirely submerged in the liquid of the well.

The usual sucker rod R being attached to the piston P by means of the valve cage D, when the power is applied to the pump, the piston P will slide upwardly and downwardly in alternate directions, over rather than in the cylinder C and in the barrel B but not in contact therewith. At each upward stroke of the piston, valve V will open and admit fluid from the well into chamber 20 of the barrel B and above head h , due to the suction created therein, and as the piston is moved to the end of its upward stroke the chamber 20 is completely charged with the liquid. At the beginning of the ensuing downstroke, valve V will close by gravity and pressure created in chamber 20, thus causing the raising of valve V^1 for admitting the contents of chamber 20 into chamber 21 of the piston below the end of cylinder C. The continuing up-stroke of the piston will lift the contents of the piston and cylinder

for the full length of the stroke and discharge a corresponding quantity of the liquid from the pump at the top of the well, or other point of discharge. The upward movement of piston P effects the closing of the valve V^1 . At each complete cycle of operation, the operation just described is repeated.

It will be apparent to those skilled in the art relating to deep well pumps that the capacity of a pump is always limited by the size of the well casing and the pump cylinder, and especially so when the piston operates in rather than over the cylinder, thus necessitating a piston of smaller diameter than that of the cylinder in which it operates. The piston displacement is correspondingly decreased and limited without increasing the stroke to an impracticable extent.

By the use of my improved pump, however, it will be noted that the diameter of the piston very nearly approaches that of the barrel and is substantially greater than that of the cylinder through which the liquid is discharged. Thus a shorter stroke may be provided for the sucker rod and a substantially greater piston displacement is had. This insures economy in operation, greater pump capacity and otherwise more advantageous conditions than would prevail in other types of pumps under similar operating conditions.

In the use of deep well pumps a great amount of trouble, inconvenience, suspension of operations, and no little expense is incurred, due to the entrance of sand and grit from the well into the pump joints and on the wearing surfaces, which serves to clog the pump at times and score the joints and piston and cylinder surfaces so that repair and often replacements are necessary at frequent intervals. Furthermore it is generally impossible to sufficiently lubricate the wearing parts for long continued usage.

In my improved pump, as herein described and shown, due to the provision of an external rather than an internal piston, I have provided means for thoroughly lubricating the piston and cylinder, and this serves to not only lubricate the parts well but to prevent undue amounts of sand and grit from gaining access to the wearing parts and also to prevent leakage around the cylinder and a consequent loss of efficiency.

The valves V and V^1 should be as large as practicable so as to obtain a maximum discharge volume of the liquid and to further reduce the resistance to the downward movement of the piston.

It will be understood that I have described and shown a preferred form of my pump and that said disclosure is subject to change for adapting the pump to varying conditions.

What I claim is:

1. A deep well pump including a barrel having an inlet valve therein and a head

- closing the end thereof opposite said valve, a cylinder stationarily held in and of substantially smaller diameter than said barrel, and a sectional piston having a valve in one end thereof and reciprocably mounted internally of said barrel and externally of said cylinder, certain sections of said piston being spaced apart for providing a lubricant recess around said cylinder.
2. A deep well pump including a barrel having an inlet valve therein and a head closing the end thereof opposite said valve, a cylinder stationarily held in and of substantially smaller diameter than said barrel, and a piston having a valve in one end thereof and reciprocably mounted internally of said barrel and externally of said cylinder, said piston having rings engaging said cylinder and sections connecting said rings, providing an annular chamber around said cylinder for holding a lubricant.
3. A deep well pump including a barrel having an inlet valve therein and a head closing the end thereof opposite said valve, a cylinder stationarily held in and of substantially smaller diameter than said barrel, and a piston having a valve in one end thereof and reciprocably mounted internally of said barrel and externally of said cylinder, said piston having rings engaging said cylinder and sections connecting said rings, providing an annular chamber around said cylinder for holding a lubricant, an inlet chamber being provided in said barrel below said piston and communicating with the well and with said cylinder, for the purpose described.
4. A deep well pump including a barrel having an inlet valve therein and a head closing the end thereof opposite said valve, a cylinder stationarily held in and of substantially smaller diameter than said barrel, and a piston having a valve in one end thereof and reciprocably mounted internally of said barrel and externally of said cylinder, said piston having rings engaging said cylinder and sections connecting said rings, providing an annular chamber around said cylinder for holding a lubricant, an inlet chamber being provided in said barrel below said piston and communicating with the well and with said cylinder, the valve in said barrel closing said chamber against communication with the well, and the valve in said piston closing said chamber against communication with said cylinder, at alternate movements of the piston.
5. A deep well pump including a barrel having closures at the ends thereof, a foot valve in the lower end thereof and a chamber for receiving a charge of liquid from the well, a cylinder closing a portion of the barrel at its other end and providing means for discharging liquid therefrom, a hollow piston slidable externally over said cylinder and of smaller diameter than said barrel, and a valve in said piston for admitting liquid to the piston and cylinder on the down-stroke of the piston for discharge on the up-stroke thereof, said piston composed of alternating sections and rings, providing recesses between the rings for holding a lubricant.

HARRY BELOIT.
